BY
F. J. O'Leary
ATTORNEY.

UNITED STATES PATENT OFFICE.

LESLIE E. WESTOVER, OF DENVER, COLORADO.

LAMP.

Application filed June 21, 1922. Serial No. 569,908.

To all whom it may concern:

Be it known that I, LESLIE E. WESTOVER, a citizen of the United States, residing at Denver, in the county of Denver and State 5 of Colorado, have invented certain new and useful Improvements in Lamps, of which the following is a specification.

My invention relates to improvements in lamps of the type used for illuminating 10 distant places or objects and its principal object is to provide a lamp in which the glare of the light produced therein is eliminated without diminution of the intensity of the emitted rays. With this object in view, my 15 invention is particularly adapted for use as a head light for automobiles, locomotives and other motor driven vehicles, or as a dirigible spot light of the kind used on vehicles and in theatres.

20 An embodiment of the invention has been illustrated in the accompanying drawings in the various views of which corresponding parts are similarly designated, and in which—

25 Figure 1 represents a partially sectional side elevation of a head light constructed in accordance with the present invention;

Figure 2, a vertical section taken on the line 2—2, Figure 1;

30 Figure 3, a horizontal section along the line 3—3, Figure 1; and

Figure 4, a front elevation of the head light drawn to a reduced scale.

Referring more specifically to the drawings, my improved lamp consists of a housing 5 having in its upper portion a glass-covered opening 6 through which the light rays are emitted. Facing the opening in a slanting position, is a reflector 7 upon which 40 impinge the light rays originated in a source which is concealed in the lower portion of the housing.

The source of light consists in the construction shown in the drawings, of an incandescent bulb 8 which receives its electric current through conductors 9 terminating in a socket 10 in the bottom of the housing, and said bottom is preferably concaved and 45 interiorly polished to function as a reflector 21 which throws the light produced by the bulb, in the direction of the slanting reflector which reflects the light rays toward the glass-covered opening of the lamp. The 50 reflective bottom portion of the housing in which the lamp is mounted, is preferably

covered by a glass plate 12 and above this plate are fastened a plurality of parallel equidistantly spaced partitions 13 to provide a series of narrow passages 14 which direct the light rays along parallel lines to 60 the surface of the slanting reflector. The main function of these passages is the formation of a light beam passing through the opening of the housing substantially devoid of excessively upwardly or laterally directed rays, which are the principal cause of the glare which, especially in head lights of automobiles, are an annoyance and source of danger to pedestrians and to drivers of approaching vehicles. 70

The housing may be provided with a second, smaller opening 15 below the other, which if covered by a prismatic, preferably colored glass 16, provides a pilot light which shows the direction in which the vehicle on 75 which the lamp is mounted, travels. This second opening is however, merely an adjunct feature of the invention, and has no bearing on its function of producing a light beam of maximum intensity without glare. 80

The slanting reflector as shown in the drawings, is concaved to direct the reflected rays toward the central portion of the glass covered opening and, by intersection of the rays, produces a spreading light which illuminates the sides of the road as well as the part of the same which is directly forward of the vehicle. The reflector may however be made convex when a wider spread of light rays of lesser intensity is desired, 85 or flat when it is preferred to concentrate the light rays to an area of limited diameter. 90

It is preferred to mount the reflector so that its angle may be varied in order to 95 adjust the direction in which the light beam is emitted through the opening of the housing, according to the position in which the lamp is placed on the vehicle. With this in view, one end of the reflector is pivotally 100 supported in bearings 17 on the housing and its opposite end is held in place by a bellows connection 18 which, by means of a tube, 19, communicates with a conveniently located source of fluid pressure. 105

The above described method for adjusting the reflector has been heretofore used in other different apparatus and no claim is made as to the novelty of its specific construction. 110

The glass plate 20 which covers the main opening 6 of the housing may be made of any desired sectional form, a plano-convex or convexo-concave shape being preferred. 6 The plates 13 which direct the light rays from the source of light to the slanting reflector in parallelly lined groups, are made of thin metal the sides of which are coated in a dull black or other light-absorbing 10 non-reflective color.

Having thus described the construction of my improved lamp, it will be readily seen that owing to the concealed position of the lamp and the uniform angles at which the 15 light rays impinge upon the slanting reflector, the glare which in other lamps is a constant source of annoyance and danger to pedestrians and drivers of other vehicles, is completely eliminated while by reason of the 20 specular reflection of the light rays originated in the electric bulb, the elimination of the glare does not detract from their original illuminative power.

I desire it understood that within the 25 spirit and scope of my invention as herein described and as defined in the hereunto appended claim, I may avail myself of variations in the form, construction and ar-

rangement of its parts from that shown in the drawings. 30

What I claim and desire to secure by Letters-Patent is:—

A headlight comprising an elongate housing having a glass-covered opening for the emission of light adjacent an end thereof, a source of light in the housing at its opposite end, a reflector disposed to reflect the light of said source toward the end of the housing provided with the opening, and a second reflector angularly disposed relative to the first reflector and the opening to bend the reflected light rays toward the latter, and a series of parallel partitions dividing the passage in the housing between the reflectors into channels adapted to 40 restrict the light rays so that they may pass through the opening in substantially parallel relation to each other, the housing having opposite and in spaced relation to said series of partitions, a second glass-covered 45 opening for the emission of light at a reduced intensity.

In testimony whereof I have affixed my signature.

LESLIE E. WESTOVER.
